CLAIM

The ornamental design for a cup, as shown and described.

DESCRIPTION

FIG. 1 is a front perspective from below view of a cup according to our new design;

FIG. 2 is a front perspective from above view thereof;

FIG. 3 is a front elevational view thereof;

FIG. 4 is a left-side elevational view thereof;

FIG. 5 is a rear elevational view thereof;

FIG. 6 is a right-side elevational view thereof; and,

FIG. 7 is a top plan view thereof.

The broken lines depict portions of the cup that form no part of the claim.
